COSMETIC RACK FOR LIPSTICK HOLDERS, MAKEUP PENCILS, BOBBIE PINS AND THE LIKE

Lewis S. Hollins, 1 Chester Drive, Great Neck, N.Y.

Filed Feb. 27, 1964, Ser. No. 78,800

Term of patent 14 years

(Cl. D86—10)

Fig. 1.

Fig. 2.

Fig. 3.

Fig. 4.

Fig. 5.

FIG. 1 is a front elevational view of a cosmetic rack for lipstick holders, makeup pencils, bobbie pins and the like, showing my new design;

FIG. 2 is a top plan view thereof;

FIG. 3 is a bottom plan view thereof;

FIG. 4 is a rear elevational view thereof; and

FIG. 5 is a left side elevational view thereof.

I claim:

The ornamental design for a cosmetic rack for lipstick holders, makeup pencil bobbie pins and the like, substantially as shown.
